BARREL

Jerome S. Heisler, Anthony J. Starr, Wolfgang Liebertz, and Eric Glenn, Wilmington, Del., assignors, by mesne
assignments, to Container Corporation of America,
Chicago, Ill., a corporation of Delaware

Filed June 25, 1963, Ser. No. 75,506

Term of patent 14 years

(Cl. D58—3)

FIG. 1

The rear and side not shown are substantially the same as the front and side shown.

We claim:

The ornamental design for a barrel, substantially as shown and described.
